UNITED STATES PATENT OFFICE.

AUGUST W. DONOP, OF NIAGARA FALLS, NEW YORK, ASSIGNOR, BY MESNE ASSIGNMENTS, TO U. S. LIGHT & HEAT CORPORATION, OF NIAGARA FALLS, NEW YORK, A CORPORATION OF NEW YORK.

COMPRESSIBLE RHEOSTAT.

Application filed April 17, 1914. Serial No. 832,450.

To all whom it may concern:

Be it known that I, AUGUST W. DONOP, a citizen of the United States, residing at Niagara Falls, in the county of Niagara and State of New York, have invented new and useful Improvements in Compressible Rheostats, of which the following is a full, clear, concise, and exact description, reference being had to the accompanying drawing, forming a part of this specification.

This invention relates to improvements in compressible rheostats.

Compressible rheostats generally comprise a plurality of contacting electrodes of carbon or other suitable material, which are adapted to vary the resistance of the circuit in which they are connected, by variations in pressure applied to the electrodes.

In compressible rheostats heretofore employed, the electrodes have been arranged in the form of a pile of discs or blocks of carbon or other material, one end of the pile being pressed against a relatively fixed abutment, while a movable abutment at the other end may be moved to vary the pressure exerted on the pile. With such a construction, the variations in pressure are not communicated uniformly throughout the pile, the cohesion between the discs or blocks apparently causing the electrodes adjacent the fixed abutment to be maintained in a more or less packed condition. The result is that the greater portion of the variations in resistance is controlled by the discs adjacent the movable abutment, so that the number of discs employed must be relatively great in proportion to the amount of energy dissipated in the rheostat. Furthermore, when the pressure has been greatly relaxed to obtain a maximum resistance, the discs at the movable end may become sufficiently loosened and separated to cause sparking and pitting, and sometimes rapid oxidation of the carbons.

An object of the present invention is to provide a compressible rheostat of increased effectiveness in proportion to the amount of movement of the operating member.

Another object of the invention is to provide a compressible rheostat of small size in proportion to its range.

Another object of the invention is to provide a compressible rheostat in which variations in pressure will be transmitted sub-

stantially uniformly throughout the rheostat.

Another object of the invention is to provide a compressible rheostat in which the tendency to spark and burn between the elements when under minimum pressure, is reduced.

Compressible rheostats of this type are especially adapted for use in car lighting systems, and the invention has therefore been illustrated in connection with such a system, although obviously it may be employed in many other systems.

In the accompanying drawings—

Figure 1 illustrates diagrammatically, one embodiment of the invention applied to regulate the generator in a car lighting system.

Figure 2 illustrates diagrammatically a modified embodiment applied to regulate the lamp circuit of a car lighting system.

The car lighting system diagrammatically illustrated in Figure 1, includes a generator of any preferred type, herein illustrated as having an armature 1 and a shunt field winding 2. The generator supplies a storage battery 3 and lamps or other translating devices 4, which are connected in parallel branches across the generator leads 5 and 6. An automatic switch 7, of any preferred type, may be arranged in one generator lead to connect the generator to the load at the proper voltage.

In Figure 1 the improved compressible rheostat is arranged in series with the shunt field winding. The rheostat includes a series of discs 8 of carbon or other material, the resistance of which will depend on the pressure applied to the series. The discs 8 are arranged in contact with each other and are confined between the movable abutments 9. The abutments 9 are movable towards or from each other by means of a bell crank lever 10 for each abutment. These levers 10 are pivoted at 11 and have their short arms connected as by the pivoted links 12, to the respective abutments 9. The longer arms of the levers are pivotally connected to a common operating member 13, which in Figure 1 forms the core of the electro-magnetic winding 14. In the arrangement illustrated, the winding 14 is connected in series with the generator armature so as to maintain substantially constant cur-

rent from the generator. A dash-pot 15 may be employed to steady the action of the operating parts.

- In operation, the weight of the core, which 5 may be aided, if desired, by a spring, tends to depress the longer arms of the bell crank levers so as to exert maximum pressure on the carbon discs. With the electro-magnetic winding 14 connected as illustrated, in series 10 with the generator, any increase in generator current above a predetermined amount, will tend to raise the core 13, and thereby move the abutments 9 away from each other. This will release pressure simultaneously on 15 both ends of the pile of carbon discs, so that a very small movement of the core will produce a relatively great change in the resistance of the rheostat. By simultaneously reducing pressure at both ends of the pile, a 20 substantially uniform effect will be provided throughout the pile, so that the entire series of discs may be utilized, thereby greatly reducing the number necessary to produce a given change in resistance. Even at very 25 high generator speeds, when maximum regulating effect is demanded, the carbons will not need to be so far separated as to produce sparking or burning.

Figure 2 illustrates a slightly modified 30 form of rheostat. In this form the longer arms of the bell crank levers 10 are adjustably secured to the lever 16, pivoted at 17, and normally maintained by the spring 18 in position to exert a maximum pressure on 35 the carbons. The lever 16 may be moved in opposition to the spring to decrease pressure on the carbons, by means of a plunger of magnetic material 19, pivoted to the free end of the lever 16 and acting under the influence of the coil 20. As illustrated in this 40 figure, the rheostat may be arranged in series in a work circuit and the coil 20 connected across said circuit, so that the rheostat will tend to hold constant voltage on 45 the lamps or other devices in the circuit.

It is obvious that either form of rheostat 50 may be employed to regulate a generator as in Figure 1, or to regulate a load circuit as in Figure 2, and that either may be employed 55 in many other relations, wherever a variable pressure rheostat is suitable.

The improvements herein described are not limited to use with the specific type of 60 compressible rheostat in connection with 55 which they have been illustrated and described, but may be applied with equal ad-

vantage to rheostats in which the resistance element is in the form of granular material, and to many other forms of compressible rheostats.

60

The two embodiments specifically described are merely for the purpose of illustrating the principles of the invention and many modifications may be made in the mechanical arrangement and operation of 65 parts without departing from the invention as defined in the appended claims.

65

What I claim as new and desire to secure by Letters Patent of the United States is:

70

1. In combination, a pile of freely movable contacting electrodes, a movable abutment in contact with each end of said pile, said abutments co-operating to hold said electrodes in place and in contact with each other, said abutments being biased toward 75 each other whereby said pile is normally compressed, and a common operating means for simultaneously moving said abutments away from each other to relieve said compression.

75

2. In combination, a plurality of freely movable contacting electrodes, movable supporting means supporting said electrodes at a plurality of supporting points and biased to hold said electrodes normally in contact 80 with each other under compression, and means for simultaneously moving said supporting means to relieve the compression of said elements at a plurality of points simultaneously.

80

3. In combination, a pile of contacting electrodes, a movable abutment in contact with each end of said pile, bell crank levers adapted to move said abutments relative to each other, and a common operating means 90 adapted to move said bell crank levers to simultaneously operate the same.

90

4. In combination, a pile of contacting electrodes, a movable abutment in contact with each end of said pile, a bell crank lever 100 adapted to move each abutment, means tending to move said levers to compress said pile, and a common operating means adapted to move said levers to simultaneously release the compression at each end of said pile.

100

In witness whereof, I have hereunto subscribed my name in the presence of two witnesses.

AUGUST W. DONOP.
